WINDING MACHINE

Thomas N. Carter, Bayside, N. Y., assignor to
 Cameron Machine Company, Brooklyn, N. Y., a
 corporation of New York

Application January 6, 1950, Serial No. 137,094

5 Claims. (Cl. 242—66)

1

This invention relates to improvements in winding machines for winding web material on a winding roll which is driven by a surface winding drum and a top pressure or riding roll. The invention relates more especially to the drive and related mechanism for the top pressure or riding roll. As illustrative of the invention the present embodiment shows a slitting and rewinding machine, and for purposes of simplicity only such features will be shown and described as are necessary or helpful for an understanding of the invention.

As is well known, in machines of this type it is customary at the commencement of the operation for the operator to "inch" the winding drum by slipping the clutch, such as a friction clutch, to drive the winding drum at a much less speed than that normally provided. Due to the heat generated under slippage, and centrifugal force exerted, great difficulty has been experienced in maintaining the clutch in condition to accurately maintain desired tension on the web being wound under variable conditions. Also, the up and down movement of the riding roll due to the accumulation of material on the winding roll and the difference in the counterweights imposed on opposite ends of the riding roll exert uneven or unbalanced stresses on the riding roll and its drive.

An object is to provide an improved mounting means and means for driving the riding roll from the winding drum.

Further objects and advantages of the invention will more fully appear from the following description taken in connection with the accompanying drawings which show, by way of example, the present preferred embodiment of the invention.

Referring to the accompanying drawings in which the same reference characters indicate the same parts in the various views:

Fig. 1 is a front elevational view of a machine embodying my invention;

Fig. 2 is an end elevation of the machine shown in Fig. 1, showing the main drive end of the machine;

Fig. 3 is a somewhat enlarged end view of the machine showing further details of the main drive end;

Fig. 4 is a front elevational view of the main drive end of said machine, partly in section;

Fig. 5 is a cross-sectional view taken on line 5—5 of Fig. 4;

Fig. 6 is a cross-sectional view taken on line 6—6 of Fig. 4;

2

Fig. 7 is a plan view, partly in section, as viewed from the line 7—7 of Fig. 6;

Fig. 8 is a somewhat enlarged front elevational view, partly in section, of a portion of the machine on the side opposite the main drive, showing further details of the riding roll drive and mounting; and

Fig. 9 is an end elevation of the mechanism shown in Fig. 8.

Referring to the drawings and more particularly to Figs. 1 and 2; the main frame is composed of a base having end frame members 1 and 2 and suitable tie members such as the bar 3, and a top portion having end frames 4 and 5 rigidly connected together near their upper ends by a tie piece 6. Suitably journaled on the base end members 1 and 2 are a front winding drum 7 and a rear winding drum 8, which jointly serve to support and surface drive a winding roll 9 having a shaft whose ends are slidably supported on respective side frame members 4 and 5 (Fig. 4). The winding drums 7 and 8 have shaft ends extending outwardly beyond the base ends 1 and carry secured thereto spur gears 10 and 11 (Fig. 5) engaged by a driving pinion 12 carried on the end of a drive shaft 13 whose inner end is suitably supported in base end 1 and whose outboard end is supported by a bracket designated in general as 14. The shaft ends with attached spur gears 10 and 11, and the driving pinion 13 and the adjacent portion of shaft 12 are enclosed within an oiltight housing 110 provided with a sight oil gauge 110'.

Main drive

Power is delivered from a suitable source (Figs. 4 and 3) by a plurality of V-belts engaging a pulley or sheave 15 which is freely rotatably mounted on the outer end of the drive shaft 13 (Fig. 4). This pulley or sheave carries an inwardly extending drum 16 having a frusto-conical inner periphery forming the driving member of a conical friction clutch. The driven member of the clutch comprises a disc wheel 17 having a hub carried on the inner end of the shaft 13 and rotatably secured thereto by a spline connection permitting free axial movement along said shaft toward and away from the driving clutch drum 16 and normally urged away from said drum by compression springs, such as 18. The friction engaging portion of the driven clutch member comprises a plurality of segments of molded heat resisting friction material, such as the segments 19, which are provided with re-

cesses aligned to engage a flange 20 carried on the wheel 17 serving to hold the segments in alignment to provide the friction engaging block assembly having an outer peripheral frusto-conical surface conforming to the frusto-conical surface of the drum 16; the individual blocks being securely clamped in position by bolts, such as 21. The driven clutch member is moved into engagement with the driving clutch part by means of a control bearing housing 22, the force being transmitted between the housing and the hub of disc 17 by suitable anti-friction bearings in a manner well known. The housing 22 is engaged by a control yoke provided on the upper end of a bell crank 23 suitably (Fig. 3) pivotally supported from a fixed part of the frame and whose other end is pivotally connected to the upper end of a clutch control rod 24 having a lower end slidably disposed in a lever pin 25 journaled on the outer end of a lever 26 operatively carried on an outboard end of a torque shaft 27 journaled in the base frame 1. The lower extremity of rod 24 is provided with a stop nut to prevent its disengagement from the pin 25. Actuating force is transmitted from the lever 26 to the rod 24 by means of a compression spring 29 surrounding the lower end of rod 24 and disposed between the pin 25 and a pair of adjustable lock nuts 30 threadedly engaged on the rod 24 to provide for adjusting the compression in spring 29. It will thus be seen that the actuating force is resiliently exerted through the spring 29. The inboard end of shaft 24 carries rigidly secured thereto (Figs. 7 and 4) a lever arm comprising a pair of spaced bars 28 between which is disposed a lock quadrant 31 which is also mounted on the shaft 27. The quadrant 31 is further supported and rigidly clamped in position on the base tie bar 3. The pair of rods 28 extend forwardly above and beyond the tie rod 3 and carry pivotally mounted at their free ends a foot treadle 32 supported for angular movement about an axis 33 and having a downwardly extending arm pivotally connected at 34 to a treadle lock rod 35 whose rear end is pivotally connected to a downwardly extending arm carried on a foot treadle lock 36 provided with a locking pin 37 whose inner end frictionally engages a smooth hardened quadrant surface 38 provided on the lock quadrant 31. It will therefore be seen that as the treadle 32 is rotated in a clockwise direction the lock pin 37 is released from locking engagement with the quadrant surface 38 permitting the control lever to return to its neutral or elevated position; and when the control lever is moved to the lower position to engage the clutch movement of the treadle 32 in an anti-clockwise direction engages the lock pin 37 against the quadrant surface 38 positively locking the mechanism in a position to give it the desired degree of engagement between the clutch members.

A suitable housing 40 (Figs. 4, 1, 2 and 3) encloses the clutch mechanism commencing adjacent the driven clutch wheel 17 and extending outwardly and over the clutch mechanism, an opening being provided in the rear side for the passage of the driving V-belts. The outer periphery of the driven clutch wheel 17 extends upwardly beyond the adjacent end of the housing 40 to provide for manual engagement by the operator to fulfill the purpose of the main drive hand wheel, permitting manual adjusting movement of the winding drums 7 and 8.

The periphery of the wheel 17 serves as a braking surface for engagement by a brake shoe 41

(Figs. 3, 4 and 6) pivotally mounted at its rear end to a fixed bracket 42 and pivotally connected at its forward end to a brake rod 43 whose lower end is suitably secured to a brake release lever 44 secured to the outboard end of the shaft 27 (Fig. 7) for movement thereby when the clutch control lever 28 is moved downwardly to drivingly engage the clutch. The brake rod 43 passes through a compression spring 45 whose upper end engages an adjustable stop nut 46 and whose lower end is anchored on a fixed bracket 47. By adjusting the nut 46 the desired braking force may be exerted upon the brake shoe 41; so that upon release of the clutch engagement the spring 45 will automatically exert braking force against the wheel 41 to resist the rotation of the drums 7 and 8. A suitable brake handle 48 is provided on the brake shoe 41 to permit additional manual braking when desired.

Riding roll

Referring more particularly to Figs. 1 and 2; a riding roll 50 is rotatably journaled at one end in a bearing block 51 slidably mounted on a suitable guideway 52 (Fig. 3) carried on the upper frame member 4, and its opposite end is suitably rotatably mounted in a journal block 53 (Fig. 8) slidably mounted on a guideway 54 provided on the upper frame member 5 and oppositely disposed in parallelism with the corresponding guideway 52. The riding roll 50 is supported in a well known manner from sprocket chains 55 and 56 provided with variable counterweights 57 and 58, by means of which the pressure exerted by the riding roll on the rewind roll 9 may be varied from one end of the roll to the other in the customary manner to accommodate operating conditions. Conventional means for lifting the riding roll comprises the hand lift wheel 59 operatively connected for suitable sprocket and chain mechanism designated in general as 60 for exerting lifting movement upon the chains 55 and 56. Substantial parallelism of the riding roll 50 is provided in a conventional manner by an elevated rack pinion shaft 60 carrying at its opposite ends pinions respectively engaging racks 62-63 provided on the opposite frame members 1 and 2. A riding roll tie rail 64 (Fig. 1) has one end secured at 65 (Fig. 4) to the slideable journal block 51 and its opposite end (Fig. 8) rigidly secured, as by spaced bolts 66, to the slideable journal block 53 for a lateral extent spanning the guide rail 54 and the riding roll driven pinion 70 to be more particularly described below. I have found that this provides an efficient means of taking the unequal strain imposed upon the riding roll 50 due to the unequal pressure exerted on the riding roll at its opposite ends and the delivery of the driving force at one end of the riding roll only. This provision is important, since it relieves the stresses which would otherwise be imposed on the journal blocks, guideways and rack and pinion connection, with the attendant friction.

Riding roll drive

Referring more particularly to Figs. 8 and 9; a shaft end 67 of the riding roll 50 is supported in the journal block 53 by means of the ball bearing 68 adjacent to which is disposed an oil seal ring 69. A driven pinion gear 70 is secured to the end of the shaft end 67 closely adjacent the side frame 5 and is in driving engagement with an intermediate spur gear 71 secured to a stub shaft 72 journaled in spaced apart ball bearings

73—74, the outer of which is enclosed by an oil seal cap 75. An intermediate bevel gear 76 formed as an integral part of the spur gear 71 is in driving engagement with a driven bevel gear 77 fixed on a quill shaft 78 which is rotatably journaled in an upper ball bearing 79 and a lower ball bearing 80; the bearings 79 and 80 each being provided with an oil seal ring. The bearings 79 and 80 are carried respectively on the upper and lower ends of a housing section 81 which is rigidly secured to the journal block 53 and therewith provides an oiltight housing for the gear train 70—71, inclusive; an oil sight 81' preferably being provided in the housing. The quill sleeve 78 is drivingly connected to and freely axially slidably on a spline quill shaft 83 whose upper end extends a sufficient distance to accommodate the full travel of the journal block 53 and whose lower end is provided with a smooth diameter freely rotatably within a driving sleeve 84 and supported axially thereby. The sleeve 84 is journaled in an upper ball bearing 85 and a lower ball bearing 86 supported in an oiltight housing designated in general as 87 secured rigidly to the base frame member 2 and provided with a sight oil gauge 87'. The sleeve 84 carries secured thereto a driven bevel gear 88 in driving engagement with an intermediate bevel gear 89 formed as a part of an intermediate spur gear 90 freely rotatably mounted by means of spaced ball bearings 91, on a stub shaft 92 which is rigidly bolted to the housing 87 in oiltight relationship therewith. The intermediate spur gear 90 is in driven engagement with a pinion gear 93 fixed to the outboard shaft end of one of the winding drums, in the present instance front drum 7. For frictionally connecting the driving sleeve 84 with the quill shaft 83 the following more or less conventional clutch means is employed. The lower outwardly extending end of sleeve 84 is rotatably connected to a drive case 94 rotatably connected to a friction drive washer 95. The lower end of the quill shaft 83 is splined as at 96 and carries thereon a pair of friction collars 97 disposed on respectively opposite sides of the friction washer 95. The clutch parts 94—97 are held in assembled position by means of friction lock wheels 98 threadingly engaged on the lower end of shaft 83 and between which and the lower friction collar 97 is interposed a compression spring 99.

It will thus be seen that as the winding drum 7 is rotated the desired driving force is transmitted through the clutch mechanism 94—99 to the shaft 83 which is in continuous driving connection with the riding roll 50 during its full limit of travel. It will be noted that the upper gear drive assembly associated with the riding roll 50 is disposed in close proximity to the guideway carrying the journal block 53; and this augments the function of the spanning connection of the tie bar 64 with the journal block 53 in accommodating the stresses involved.

Having thus described my invention with particularity with reference to its presently preferred form, it will be obvious to those skilled in the art, after understanding my invention, that other changes and modifications may be made therein without departing from the spirit and scope of my invention, and I aim in the appended claims to cover such changes and modifications as are within the scope of the invention.

What I claim is:

1. In a machine of the character described the combination of a horizontal rotatable shaft supported in fixed journals and having a driving

70
75

pinion gear fixed to one end, a riding roll supported above said shaft in journal blocks slidably carried respectively on parallel upright guide rails and having a driven pinion fixed to its axle end, and means for driving said riding roll from said rotatable shaft throughout the travel of said riding roll comprising, an axially fixed sleeve journaled for rotation in an oiltight gear housing, gear means within said housing drivingly connecting said sleeve to said driving pinion, a quill shaft disposed parallel to said guide rails and having its lower end freely rotatably passing through said sleeve and supported axially thereby, adjustable friction means connecting said sleeve and shaft, a quill sleeve freely slidably disposed on said quill shaft and continuously rotatably connected thereto, an oiltight gear housing provided in part by one of said journal blocks and carrying said quill shaft rotatably journaled therein, a driving bevel gear secured to said quill sleeve, a combined bevel and spur intermediate gear drivingly connecting said driving bevel gear and said driven pinion gear.

2. In a machine of the character described the combination of a horizontal rotatable shaft supported in fixed journals and having a driving pinion gear fixed to one end, a riding roll supported above said shaft in journal blocks slidably carried respectively on parallel upright guide rails and having a driven pinion fixed to its axle end, and means for driving said riding roll from said rotatable shaft throughout the travel of said riding roll comprising, an axially fixed sleeve journaled for rotation and restrained axially in a gear housing, gear means within said housing drivingly connecting said sleeve to said driving pinion, a quill shaft disposed parallel to said guide rails and having its lower end freely rotatably passing through said sleeve and supported axially thereby, adjustable friction means connecting said sleeve and shaft, a quill sleeve freely slidably disposed on said quill shaft and rotatably connected thereto, a gear housing provided in part by one of said journal blocks and carrying said quill shaft rotatably journaled therein and fixed axially thereto, a driving bevel gear secured to said quill sleeve, a combined bevel and spur intermediate gear drivingly connecting said driving bevel gear and said driven pinion gear, and a tie rod having one end rigidly secured to said combined journal block and housing throughout a lateral extent spanning said guide rail and driven pinion, the other end of said tie rod being attached at its opposite end to the other of said journal blocks.

3. In a winding machine of the type wherein a winding roll displaceable by accumulation of material is adapted to be supported from laterally spaced frames with its lower periphery engaged by a winding drum, and its upper periphery engaged by a displaceable riding roll, means for driving said riding roll from said drum comprising a quill shaft having its lower end extending below said drum and its upper end extending above the uppermost position of said riding roll, a drive sleeve freely rotatably surrounding the lower end of said quill shaft and supporting the same axially, a housing in which said sleeve is axially fixed and rotatably journaled, the lower end of said shaft extending below said housing and sleeve, an adjustable friction clutch drivingly connecting the lower ends of said shaft and sleeve, a gear train disposed within said housing and drivingly connecting said drum and said sleeve, a quill sleeve axially slidably along and

rotatably engaged by said quill shaft, an upper gear box in which said quill sleeve is rotatably journaled and axially fixed, a journal block for one end of said riding roll slidably supported for movement on one of said frames in a direction parallel to said quill shaft, a gear train within said upper gear box and drivingly connecting said quill shaft and said riding roll, a second journal block for the other end of said riding roll slidably mounted on the other of said frames for movement in a direction parallel to said first journal block, and a tie bar connected at one end to said second journal block and having its other end rigidly connected to said first journal block.

4. In a winding machine of the type wherein a winding roll displaceable by accumulation of material is adapted to be supported from laterally spaced frames with its lower periphery engaged by a winding drum, and its upper periphery engaged by a displaceable riding roll, means for driving said riding roll from said drum comprising a quill shaft having its lower end extending below said drum and its upper end extending above the uppermost position of said riding roll, a drive sleeve freely rotatably surrounding the lower end of said quill shaft and supporting the same axially, an oiltight housing in which said sleeve is axially fixed and rotatably journaled, the lower end of said shaft extending below said housing and sleeve, an adjustable friction clutch drivingly connecting the lower ends of said shaft and sleeve, a gear train disposed within said housing and drivingly connecting said drum and said sleeve, a quill sleeve axially slidably along and rotatably engaged by said quill shaft, an upper oiltight gear box in which said quill sleeve is rotatably journaled and axially fixed, a journal block for one end of said riding roll and slidably supported for movement on one of said frames in a direction parallel to said quill shaft, a driving bevel gear secured to said quill sleeve, an intermediate bevel gear engaging said driving bevel gear and having an integral spur gear in driving engagement with a pinion gear carried on a shaft end of said riding roll, said gears being disposed within said upper gear box, a second journal block for the other end of said riding roll slidably mounted on the other of said frames for movement in a direction parallel to said first journal block, and a tie bar connected at one end to said second journal block and having its other

end rigidly connected to said first journal block by spaced attachment means supporting said tie bar as a cantilever from said first journal block and its associated housing and gear train.

5. In a winding machine of the type having laterally spaced frames for supporting a winding roll displaceable by accumulation of material thereon, a winding drum for surface driving engagement with an under portion of said winding roll, and a riding roll for driving engagement with an upper portion of said winding roll and displaceable thereby, means for driving said riding roll during its displacement comprising a driving pinion gear rotatable with said drum, an intermediate spur gear driven by said pinion and provided with an intermediate bevel gear, a bevel gear driven by said intermediate bevel gear, a drive sleeve to which said driven bevel is affixed and extending upwardly and downwardly therefrom, 10 an oiltight housing enclosing said sleeve, a riding roll drive quill shaft having a lower end freely rotatable in said sleeve and extending beyond the lower end thereof, adjustable friction clutch means interconnecting said lower shaft end and sleeve, a driven pinion gear secured to said riding roll, an intermediate spur gear in driving engagement with said driven pinion and provided with an intermediate bevel gear, a driving bevel gear in mesh with said intermediate bevel gear, 15 an oiltight housing enclosing said gears and having spaced bearings supporting said sleeve, the said quill drive shaft freely slidably passing through said quill sleeve and being rotatably secured thereto, 20 said riding roll housing being provided in part by a bearing block for said riding roll slidably supported on said frame.
